UNITED STATES PATENT OFFICE.

WILLIAM H. GEORGE, OF FAIRFIELD, IOWA, ASSIGNOR TO THE DEXTER COMPANY, OF FAIRFIELD, IOWA, A CORPORATION OF IOWA.

GEARING.

1,419,247.

Specification of Letters Patent. Patented June 13, 1922.

Application filed February 5, 1920. Serial No. 356,558.

To all whom it may concern:

Be it known that I, WILLIAM H. GEORGE, a citizen of the United States, and a resident of Fairfield, in the county of Jefferson and State of Iowa, have invented certain new and useful Improvements in Gearing; and I do hereby declare that the following is a full, clear, and exact description thereof, reference being had to the accompanying drawings, and to the letters of reference marked thereon, which form a part of this specification.

This invention relates to improvements in gearing, and consists of the matters herein- 15 after described and more particularly pointed out in the appended claims.

The object of the invention is to provide a simple and efficient gearing more particularly adapted for embodiment in a washing machine, for imparting a rocking or oscillating movement to the water and clothes-receiving container thereof for the purpose of washing the clothes.

The advantages of the invention will be 25 more fully set forth as I proceed with my specification.

In the drawings:-

Fig. 1 illustrates a view in side elevation of a washing machine embodying my im- 30 proved gearing.

Fig. 2 illustrates a horizontal, sectional view through the washing machine, in a plane indicated by the line 2-2 of Fig. 1.

Fig. 3 illustrates, on an enlarged scale, a 35 face view of the gear casing with the front cover plate removed.

Fig. 4 illustrates a horizontal section through the gear casing, in a plane indicated by the line 4-4 of Fig. 3.

Fig. 5 illustrates a vertical section through the gear casing, in a plane indicated by the line 5-5 of Fig. 3.

Referring now in detail to that embodiment of the invention illustrated in the accompanying drawings, 10-10 indicates the side frame members, each of which consists of an inverted U-shaped member made of channel iron. Each frame member includes a horizontal top rail 11, and upright bars 12, that provide the legs for the washing machine as a whole. The two legs 12, of each frame 10, are connected together near their bottom ends by angle bars 13, while the like legs of each frame are connected together by front and rear end bars 14 and

15 respectively, there being an intermediate bar 16, connecting the angle bars 13 together between their ends. The construction just described provides a light, rigid frame or support upon which the rest of the mechanism is mounted.

At the middle of each top rail 11, is secured a bearing block 17, in which is journaled the trunnions 18 of rocking or oscillating clothes receiver 19, which is adapted to rock about said trunnions as an axis, in a path parallel to the side frame members 10. As shown, said clothes receiver has horizontal top and bottom walls 20 and 21, and semi-cylindric end walls 22 and flat upright side walls 23, to which are secured brackets or spiders 24 that carry the trunnions 18 before referred to. In the top wall of the clothes receiver 19, is a door 25, through which the clothes to be washed are placed within, and removed from said receiver. One of the spiders 24 is provided with a stud 26 which is spaced from the trunnion 18, the purpose of which will presently appear.

30 80 85 90 95 100 105 110

30 indicates a gear casing which includes a removable, upright cover plate 31. This cover plate has a hollow boss 32 which rests upon and is secured to one of the angle bars 13 of the frame, by means of bolts passing through ears 33 made integral with said hollow boss. Journaled at one end in said gear casing is a horizontal shaft 34, the opposite end of which is journaled in a bearing block 35, secured to another brace 36 (see Fig. 2) that connects the rear end and intermediate frame bars 15 and 16 respectively together. Fixed to this end of the shaft 34, outside of the bar 36, is a crank arm 37 which is connected by a pitman, or link 38 to the stud 26 on the clothes receiver 19. Thus, as is apparent when the shaft 34 is rotating, a rocking or oscillating movement is imparted to the clothes receiver through the crank arm 37, link 38 and stud 26 respectively.

Fixed to that end of the shaft 34, within the gear casing is a clutch member 40 (see Fig. 5) and loosely mounted on said end of said shaft and capable of a longitudinal movement thereon, toward and away from the clutch member 40, is a spur pinion 41. This pinion includes a clutch member 42, which is adapted to be engaged with and disengaged from the clutch member 40, before referred to. The pinion 41 is also provided

at that end opposite the clutch member 42 with a groove 43, for a purpose to be set forth later.

The pinion 41 meshes with a pinion 44, formed on the hub of a large spur gear 45, which is rotatively mounted on a short shaft 46, fixed in the upright walls of the gear casing and cover plate, respectively. This spur gear which also includes a bevel pinion 47, meshes with a pinion 48 fixed to a horizontal shaft 49, journaled in said gear case. To that end of the shaft 49, without the gear case is fixed a grooved pulley 50, driven by a belt 51, from a smaller pulley 52 on the armature shaft of an electric motor 53. Preferably, I hang said motor from the under side of a board or like support 54, which is secured at one end to the frame bar 14, and is secured at its other end to a hanger 55, depending from the intermediate bar 16 of the frame.

In the hollow boss 32, of the cover plate 31, is journaled the bottom end of an upright shaft 60, and fixed to said shaft within said boss is a bevel pinion 61 that meshes with the bevel pinion 47 formed integral with the large spur gear 45. The top end of this shaft is journaled in a bearing 62, on a shelf or board 63, located in a plane above the top of the clothes receiver 19, said shelf being secured to suitably bent bars 64 rising from and secured as shown to each side member 10 of the frame. The top end of the shaft is squared to engage in the gear box of a clothes wringer (not shown) which is adapted to be swung into different positions about the said shaft as an axis.

Associated with the longitudinally shiftable gear pinion 41 on the shaft 34, is a clutch shifting member 70, the forked bottom end of which engages in the groove 43, provided therefor in said gear pinion. The top end of said shifter which extends upwardly through a slot 71 in the top wall of the gear casing has a horizontal stem 73 which extends through a hole 74 in an ear 75 of the cover plate, there being a spring 72, surrounding said stem between said ear and the top end of said shifter member 70, which acts normally to engage the clutch member 42 with the clutch member 40 on the shaft 34.

On the outer, free end of the stem 73, is a plate 76 which is adapted to be engaged by the horizontally bent end 77 of an upright control rod 78 which is journaled at its top and bottom ends in the ear 75 of the cover plate and a bearing bracket 79 on the top member of the adjacent side frame 10. The top end of said control rod is bent as at 80 to provide a handle by means of which the control rod is actuated.

The operation of the improved gearing as above described, is as follows: Assume that the motor 53 is running to drive the pulley

and shaft 50 and 49 respectively. This will through the gear 45 drive continuously the upright shaft 60 and the gear 41 which is loose on the shaft 34. When it is desired to drive the shaft 34 to impart a rocking or oscillating movement to the clothes container 19, the handle 80 of the control rod is actuated to move the bent lower end 77 away from the plate 76 on the stem 73 of the clutch shifter 70 when the spring 72 will act to move the shifter 70 to the right as shown in Fig. 5, to cause an engagement between the clutch members 40 and 42 respectively. When the clutch members are thus engaged, the gear pinion 41 which is meshing with the pinion 44 of the gear 45, will impart a driving connection to the shaft to thus rock the clothes receiver as before described.

To stop the movement of the clothes receiver, the operator actuates the rod 78, so that its bent, lower end 77, will engage the plate 76 and move the same outwardly, together with the clutch shifter 70 which will move the clutch member 42 and gear 41 endwise on the shaft 34 when the engagement between said clutch members is broken.

Thus by a simple movement by the operator, the actuation of the clothes receiver is readily controlled. The gearing described provides for the proper gear speed reduction between the motor and the clothes receiver and said gearing may all be assembled in said casing before the casing is attached in place. All the gearing is fully inclosed.

While in describing my invention, I have referred to certain details of mechanical construction and arrangement of parts, I do not wish to be limited thereto except as is pointed out in the appended claims.

I claim as my invention:—

1. The combination of a support, a member mounted on the support to rock about a horizontal axis, a two-part gear casing mounted on the support beneath the rocking member, a horizontal driven shaft journaled at one end in the casing and at its other end upon said support, a clutch member fixed in said shaft within the casing, a clutch pinion loose on said shaft near said clutch member, a drive shaft journaled in said casing, a pinion on the drive shaft within said casing, an intermediate shaft mounted at its ends in both casing parts, speed reducing gearing on said intermediate shaft and connecting the pinion on the drive shaft with the clutch pinion on the driven shaft, a shifting member engaged with said clutch pinion and projecting through the top of said casing, an upright rod, journaled on said casing and on said support for actuating the clutch shifting member, and means connecting the driven shaft with said member on the support, and imparting a rocking movement thereto.

2. The combination of a support, a mem-

105

115

120

125

130

ber mounted on the support to rock about a horizontal axis, a two-part gear casing mounted on the support beneath the rocking member, a horizontal driven shaft jour-
 5 nalled at one end in the casing and at its other end upon said support, a clutch mem-
 ber fixed on said shaft within the casing, a clutch pinion loose on said shaft near said clutch member, a drive shaft jour-
 10 nalled in said casing, a pinion on the drive shaft within said casing, an intermediate shaft mounted at its ends in both casing parts, a spur gear and a pinion rotative therewith on said intermediate shaft, said
 15 spur gear meshing with the pinion on the drive shaft and the pinion on said inter-
 mediate shaft meshing with said clutch pinion, a spring pressed clutch shifting mem-
 ber associated with said clutch pinion and
 20 normally urging it into engagement with said clutch member, a vertically disposed ro-
 tatable clutch shifting rod mounted at its ends in said casing and support, respec-
 tively, that end of said rod mounted in the
 25 casing having a part adapted when said rod is rotated in one direction to hold said spring pressed clutch shifting member and clutch pinion out of engagement with the clutch member, against the action of the
 30 spring, and means connecting the driven shaft with said member on the support to impart a rocking movement thereto.

3. In a gearing of the kind described, a gear case and cover therefor mounted on a support, a horizontal driven shaft and a vertical driven shaft, each having one end jour-
 35 nalled in fixed parts of the support, the other end of the horizontal driven shaft being journaled in the gear case and the other
 40 end of the vertical driven shaft being journaled in the cover, a horizontal drive shaft journaled in the casing only, a horizontal shaft intermediate said drive and horizontal driven shafts, and fixed in said gear case

and cover respectively, a combined gear ele- 45
 ment loose on said intermediate shaft and including a spur gear with a spur pinion on one side and a bevel pinion on the other side thereon, a pinion on the drive shaft meshing with said spur gear, a bevel pinion on the 50 end of the vertical driven shaft within said cover and meshing with said bevel pinion of said combined gear element, a clutch collar on said horizontal driven shaft within said gear case, a clutch pinion slideable on said 55 last mentioned shaft into and out of en-
 gagement with said clutch collar, said clutch pinion being always in mesh with the spur pinion of said combined gear element, and a clutch rod for shifting said clutch pinion. 60

4. The combination of a support, a mem-
 ber mounted on said support to rock about a horizontal axis, a horizontal driven shaft on said support, beneath said rocking mem-
 ber, a gear casing on said support, in which 65 one end of said shaft has bearing, speed
 reducing gearing in said gear casing, a motor for driving said gearing, a clutch member on that end of said shaft within said gear casing, a gear including a second clutch member also on that end of said shaft within the gear casing and meshing with said speed-reducing gearing, a spring pressed 70 clutch shifting member, having bearing without the casing, an upright actuating rod 75 for said clutch shifter, and means connect-
 ing the other end of said horizontal shaft to said rocking member and translating the rotary movement of the shaft into a rocking movement of said member. 80

In testimony that I claim the foregoing as my invention, I affix my signature in the presence of two witnesses, this 24th day of January, A. D., 1920.

WILLIAM H. GEORGE.
